Primary Examiner — Marie D. Fast Horse(74) *Attorney, Agent, or Firm* — Prakash Nama; Global IP Services, PLLC(57) **CLAIM**

The ornamental design for a USB-C dock, as shown and described.

DESCRIPTION

FIG. 1 is a front elevational view of a USB-C dock showing my new design;

FIG. 2 is a left side view thereof;

FIG. 3 is a right side view thereof;

FIG. 4 is a top plan view thereof;

FIG. 5 is a bottom plan view thereof;

FIG. 6 is a perspective view thereof; and,

FIG. 7 is another perspective view thereof.

The broken lines shown in the drawings depict portions of the USB-C dock that form no part of the claimed design.

1 Claim, 6 Drawing Sheets(56)
